UNITED STATES PATENT OFFICE

162,804

INFANT'S CRIB

Abraham G. Feldman, Chicago, Ill., assignor to Storkline Furniture Corporation, Chicago, Ill.,
a corporation of Illinois

Application September 2, 1950, Serial No. 12,037

Term of patent 7 years

(Cl. D5—5)

To all whom it may concern:

Be it known that I, Abraham G. Feldman, a citizen of the United States, residing in Chicago, in the county of Cook and State of Illinois, have invented a new, original, and ornamental Design for an Infant's Crib, of which the following is a specification, reference being had to the accompanying drawing, forming part thereof, in which the single figure of the drawing is a perspective view taken from one end and somewhat to one side of an infant's crib embodying my new and ornamental design. The characteristic features of my design reside in the portions shown in full lines in the drawing.

I claim:

The ornamental design for an infant's crib, substantially as shown and described.

ABRAHAM G. FELDMAN.
